Fig. 2

Inventor:

William S. H. Hamilton,
by *Albert G. Davis*
His Attorney.

UNITED STATES PATENT OFFICE.

WILLIAM S. H. HAMILTON, OF SCHENECTADY, NEW YORK, ASSIGNOR TO GENERAL ELECTRIC COMPANY, A CORPORATION OF NEW YORK.

CONTROL SYSTEM AND APPARATUS FOR AIR COMPRESSORS.

Application filed January 28, 1921. Serial No. 440,767.

To all whom it may concern:

Be it known that I, WILLIAM S. H. HAMILTON, a citizen of the United States, residing at Schenectady, county of Schenectady, State of New York, have invented certain new and useful Improvements in Control Systems and Apparatus for Air Compressors, of which the following is a specification.

My invention relates to the control of 10 electrically driven air compressors, and in particular to the control of air compressors for railway train units.

Such air compressors are ordinarily operated by means of electric motors energized 15 from the trolley circuit, and the motors are controlled responsively to the reservoir air pressure through a low potential circuit. A motor generator operated from the trolley circuit is usually provided for furnishing the low potential for the control circuits. A synchronizing wire is ordinarily provided to interconnect the compressor control equipments on the various train units so that all of the compressors are simultaneously stopped when all of the reservoirs 20 have been charged to at least the upper pressure limit; or in other words, the last reservoir to be charged to the pressure limit controls all of the compressors. Such equipments have heretofore had the disadvantage that it was necessary to operate the motor generators during both single unit and multiple unit operation. It is wasteful of power to operate the motor generator on a 25 train unit at all times, because when the unit is standing idle the power consumed by the motor generator is practically wasted. It has heretofore been proposed to employ a storage battery to furnish the low potential 30 control power instead of the motor generator set, but a storage battery is expensive, it is heavy, it requires considerable maintenance, and it is inefficient. It has also been proposed to energize the control wiring 35 directly from the trolley circuit, but that is impractical where the trolley voltage is relatively high, as is the case in modern long distance electrifications, because of the fact that the synchronizing wire is usually included in a cable running between the cars 40 along with other control wires, and serious trouble will result if this wire becomes accidentally crossed with any of the other control wires.

One of the objects of my invention is to 55 provide an improved arrangement, employing a suitable source of low potential such as a motor generator, in which the control of the compressor motor on each train unit is dependent on the low potential source 60 only for multiple unit synchronous operation. In case the low potential source is a motor generator set, it may be shut down when the train unit is standing idle, or in case the motor generator set is disabled 65 while the train unit is operating in a train with other units, the compressor on that train unit may continue to operate to give fairly good results.

Another object of my invention is the provision of an arrangement in which all the compressors on the various train units are automatically shut down when any one of the reservoirs has been charged to the predetermined value, regardless of the fact 70 that the other reservoirs may not be charged to as high a pressure. Power is therefore saved, since to wait until all of the reservoirs are charged to the predetermined pressure may mean that one or more of the reservoirs may be charged beyond the required 75 pressure, and the air is therefore wasted through the operation of relief valves. The pressure of the various reservoirs will equalize so that none of them will be charged 80 beyond the pressure limit, thus saving air and power.

Certain advantageous features of construction and arrangement of my invention will be pointed out particularly hereinafter. 85

For a better understanding of my invention, reference is had to the accompanying drawings showing an embodiment of my invention for purposes of illustration, and in which Fig. 1 shows in simplified diagram the air compressor system on a single train unit, and Fig. 2 shows the manner in which the train units are interconnected by means of a synchronizing wire in order to carry 90 into effect certain of the objects of my invention.

Referring to Fig. 1, the motor driven air compressor having an electric motor 10 driving a compressor 11 for the purpose of charging a reservoir 12 is adapted to supply 100 compressed air to a compressed air braking system for a railway train unit. Since my invention is applicable generally to com-

pressed air systems, I have illustrated it in connection with a straight air braking equipment for a train unit, and have shown merely enough of the air braking equipment to 5 indicate to those skilled in the art one of the uses of my invention. This air braking system is shown in very simplified diagram, and as shown comprises an air brake cylinder 13 connected to a brake pipe 14 which is 10 controlled by means of the two engineers' valves 15 and 16 located at the front and rear respectively of the train unit. The reservoir 12 is connected to the main reservoir pipe 17. The brake pipe 14 and the 15 main reservoir pipe 17 are connected to corresponding pipes of the two braking equipments of other train units by means of the couplings shown on the ends of the pipes. Since the compressed air systems on the 20 various train units are substantially duplicates of each other, merely the one equipment has been shown, and it is to be understood that this equipment is intended to be used either singly or in connection with 25 other train units. The compressor motor 10 is adapted to be controlled responsively to the pressure set up by the compressor 11, or in other words responsively to the pressure in the reservoir 12, by means of a pneumatically operated switch 18, the details of 30 which will be hereinafter described. An electropneumatic valve 19 is adapted to control the operation of the pneumatic switch 18, and this valve is adapted to be either 35 mechanically operated by means of the electropneumatic or governor switch 20 or magnetically in response to the energization of the magnet winding 21 which is connected in the synchronizing wire 22 which inter- 40 connects the various train units.

A source of low potential comprising the motor generator set 23 is adapted to supply control power for the synchronous operation of the compressors on the various train 45 units. This motor generator set is controlled by means of the manually operated switch 24 having one set of contacts 25 which completes the circuit to the motor of the set, and another set of contacts 26 which completes the circuit from the generator of the 50 set to the synchronizing wire 22.

The pneumatically operated switch 18 is 55 provided with contacts 27 which control the energization of the compressor motor 10 from the supply circuit designated by the trolley wire 28. The movable element of the switch contacts 27 is operated by means of a pneumatic device 29 which is controlled by means of the valve 19. The pneumatic 60 switch mechanism also comprises a manually operated switch member 30 which is included in the circuit from the generator of the motor generator set to the synchronizing wire 22 and is adapted to control the supply 65 of a low potential power to the synchroniz-

ing wire. This switch member is mounted upon a sliding rod 31 suitably supported and held in the closed position by means of the spring-pressed detent 32.

As thus constructed and arranged, the 70 operation of my invention is as follows: With the parts in the various positions shown in the drawings, closing the pilot switch 33 connects the compressor motor 10 to the high potential supply circuit through 75 the contacts 27 of the pneumatically operated switch 18. The compressor 11 will operate to supply air under pressure to the reservoir 12, and when the pressure in this reservoir rises to the predetermined value, 80 the pneumatically operated switch governor 20 will mechanically raise the valve 19 so as to admit air from the reservoir 12 to the cylinder of the pneumatically operated device 29 for the switch 18. The movable member of the pneumatically operated contacts 27 will thereby be moved against the tension of the spring 34 to the open position, thereby deenergizing the compressor 85 motor 10. 90

The above described operation will take place irrespective as to whether or not the motor generator 23 is supplying control power for effecting the synchronous operation of the various compressors. Assume 95 that synchronous operation is desired. The manually operated switch 24 will be thrown to the right so as to close the switch contacts 25 and 26, and assuming that the switch rod 31 has been manually moved to the position 100 shown in the drawing at which the detent 32 holds this rod in the position so that the contact 30 completes the circuit from the generator to the motor generator set, the electromagnetic switch 35 will thereupon be 105 energized to close its contacts. If now the pneumatically operated switch 20 is caused to close by reason of the fact that the pressure in the reservoir 12 has been built up to the proper value, the magnet winding 21 of the electropneumatic valve 19 will be 110 energized and the synchronizing wire 22 will be grounded throughout. This will cause the valve magnets 21' of the other equipments to be energized through the synchronizing wire. 115

It is to be understood that I have merely shown diagrammatically the equipment of one train unit for purposes of illustration, but by reference to Fig. 2, it will be seen that I contemplate that any desired number of train units may be used. The electromagnetic switch 35' on the second train unit will be energized to close from its low potential source of supply in the same manner 125 as the switch 35 of the first equipment is energized to close. It will also be understood that the pneumatic switch 20' will be operated responsively to the pressure in the reservoir of the second equipment. 130

In case any one of the reservoirs on the various train units is first charged to the predetermined value, the pneumatic switch corresponding to the pneumatic switch 20 of

- 5 the equipment shown in Fig. 1 will close and establish a ground connection for the synchronizing wire, thereby energizing the other magnet valve or valves corresponding to the valve 19 of Fig. 1. The other valve 10 or valves will be magnetically raised and admit air under pressure from their respective reservoirs so as to operate all of the pneumatic switches corresponding to the switch 18 of Fig. 1 and thereby deenergize 15 all of the compressor motors simultaneously. A saving of power is thereby effected, since it is not necessary to wait until all of the reservoirs have been charged to the predetermined pressure. It will be obvious to 20 those skilled in the art that in certain of its aspects, however, my invention is not necessarily limited to an arrangement in which all of the compressors are shut down when one of the reservoirs has first reached 25 a predetermined pressure.

If the equipment shown in Fig. 1 is to be operated as a single unit equipment, the motor generator set 23 may be shut down. This will be effected by opening the manually operated switch 24 and tripping the 30 detent 32, thereby permitting the switch 30 to open the circuit to the synchronizing wire in accordance with the bias of the spring 34. The electromagnetic switch 35 will 35 thereby be deenergized and open the circuit for the valve magnet 21. The pneumatically operated switch 27 will now be operated directly and solely in accordance with the pressure of the reservoir 12. It will therefore 40 be seen that it will only be necessary to operate the motor generator set when multiple unit synchronous operation of a plurality of compressor equipments on various train units is desired, and that no power 45 need be wasted in the motor generator sets for the control of the compressor equipment in case the train units are operated singly.

What I claim as new and desire to secure by Letters Patent of the United 50 States, is,—

1. The combination in a compressed air system, of a motor driven compressor for supplying compressed air to the system, a source of low potential for supplying control power for controlling the compressor motor, a synchronizing wire energized from the low potential source and adapted to interconnect the control of said compressor with the control of other compressors supplying compressed air to the system, and means whereby the said compressor is adapted to control or be controlled by the other compressors of the system when the source of low potential is supplying control power, 60 and the said compressor is independently

controlled responsively to the air pressure set up by said compressor in case the source of low potential is not supplying control power.

2. The combination in a compressed air system, of a motor driven compressor for supplying compressed air to the system, a source of low potential for supplying control power for controlling the compressor motor, a synchronizing wire energized from the low potential source and adapted to interconnect the control of said compressor with the control of other compressors supplying compressed air to the system, a pneumatically operated switch for controlling the motor of said compressor, and means whereby the said switch is operated responsively to the air pressure set up by said compressor and is controlled through the synchronizing wire.

3. The combination in a compressed air system, of a motor driven compressor for supplying compressed air to the system, a source of low potential for supplying control power for controlling the compressor motor, a synchronizing wire adapted to interconnect the control of said compressor with the control of other compressors supplying compressed air to the system, a pneumatically operated switch for controlling the motor of said compressor, a valve controlling said switch, and means whereby the said valve is controlled through the synchronizing wire and is operated responsively to the pressure set up by said compressor.

4. The combination in a compressed air system, of a motor driven compressor for supplying compressed air to the system, a source of low potential for supplying control power for controlling the compressor motor, a synchronizing wire adapted to interconnect the control of said compressor with the control of other compressors supplying compressed air to the system, a pneumatically operated switch for controlling the motor of said compressor, a magnet valve controlled through the synchronizing wire for controlling the said switch, and means whereby the said valve is mechanically operated in response to the pressure set up by said compressor.

5. The combination in a compressed air system employing a plurality of motor driven compressors, of a separate switch for controlling each compressor motor, a synchronizing wire for interconnecting the control of the compressor motor switches, and means whereby all of the switches are substantially simultaneously operated to deenergize all of the compressor motors when the pressure set up by any one of the compressors first rises to a predetermined value.

6. The combination in a compressed air system employing a plurality of motor driven compressors, of a separate pneumati-

- cally operated switch for controlling each compressor motor, a synchronizing wire for interconnecting the control of the compressor motor switches, and means whereby 5 the pneumatic switch associated with each compressor motor is operated to deenergize the motor responsive to the pressure set up by the compressor driven thereby rising to a predetermined value, and the other 10 pneumatic switches are controlled through the synchronizing wire to substantially simultaneously deenergize the respective motors controlled thereby.
7. The combination in a compressed air 15 system employing a plurality of motor driven compressors, of a separate pneumatically operated switch for controlling each compressor motor, a synchronizing wire for interconnecting the control of the 20 compressor motor switches, and means whereby when the pressure set up by any one of the compressors first reaches a predetermined maximum value, the pneumatic switch associated with that compressor 25 opens and the other pneumatic switches are

controlled through the synchronizing wire to substantially simultaneously open.

8. The combination in a compressed air system employing a plurality of motor driven compressors, of a separate pneumatically operated switch for controlling each compressor motor, a synchronizing wire for interconnecting the control of the compressor motor switches, a magnet valve having its winding connected to the synchronizing wire for controlling each pneumatic switch, and means whereby when the pressure set up by any one of the compressors first reaches a predetermined maximum value, the magnet valve associated with that compressor is mechanically operated to cause its control switch to open and the other valve magnets are energized through the synchronizing wire to magnetically operate the other pneumatic switches to open 35 substantially simultaneously.

In witness whereof, I have hereunto set my hand this 27th day of January, 1921.

WILLIAM S. H. HAMILTON.
